UNITED STATES PATENT OFFICE.

NAHUM JUDSON BUSBY, OF MAPLEWOOD, MASSACHUSETTS.

ALARM-GONG.

SPECIFICATION forming part of Letters Patent No. 447,537, dated March 3, 1891.

Application filed December 17, 1889. Serial No. 334,061. (No model.)

To all whom it may concern:

Be it known that I, NAHUM JUDSON BUSBY, of Maplewood, county of Middlesex, State of Massachusetts, have invented an Improvement 5 in Alarm-Gongs, of which the following description, in connection with the accompanying drawings, is a specification, like letters and figures on the drawings representing like parts.

10 This invention has for its object to simplify and improve the construction of alarm-gongs and to increase their durability and effectiveness.

15 The alarm-gong herein to be described has a train of gearing actuated by a spring, which latter is preferably normally wound, a pallet-wheel of the train of gearing when started acting upon a pallet secured to a rock-shaft, to which is attached the hammer or striker 20 which strikes and sounds the gong. The pallet-wheel is acted upon by a holder consisting of an arm connected, preferably, in an adjustable manner to a push-rod having co-operating with it a suitable spring to normally keep 25 the push-rod out and the arm referred to pressed against one side of the pallet-wheel, the said arm when in contact with the pallet-wheel exerting sufficient friction thereon to prevent the rotation of the train of gearing, 30 and consequently at such time the gong is silent.

35 I have provided the gong with means by which to regulate, as may be desired, the amount of friction between the arm referred to and the pallet-wheel, such friction requiring to be varied according to the strength of the actuating spring or motor of the train, and also to compensate for wear between the parts by the frequent movement of the push- 40 rod.

Figure 1, in partial section, represents one of my improved alarm-gongs applied in working position. Fig. 2 is a view of the gong detached, viewing it from the right in Fig. 1, 45 the base-plate being partially broken out to show part of the gearing and hammer. Fig. 3 is a detail in two views of the arm to hold the pallet-wheel. Fig. 4 is a detail showing the same devices with part of the push-rod. 50 Fig. 5 is a perspective view of the arm and a portion of the push-rod.

A may be supposed to be part of a door or other thing to which the alarm-gong is applied for use. The base a , preferably of cast metal, receives suitable pillar-posts a' , by 55 which to support the pillar-plate a'' , the said base and plate forming a frame-work for the motor and its working parts. The base a and pillar-plate have usual or suitable bearings, such as employed in clocks or watches, to 60 sustain the motor-shaft a^3 , which is extended out through the pillar-plate and through a threaded hub a^4 , where it has applied to it a winding thumb-nut a^5 , by which to wind the motor-spring a^6 when desired, the inner 65 end of the said spring being connected in usual manner to the said shaft. The spring a^6 , the ratchet b , the pawl b' , the main gear b^2 , the pinion b^3 , gear b^4 , pinion b^5 , engaged by it, and pallet-wheel b^6 are and may be all 70 as usual, they constituting the motor mechanism for the hammer b^9 , which strikes the gong b^{10} . The arm carrying the hammer is secured to a rock-shaft b^8 , having fast on it a pallet b^7 , which is vibrated by the action of 75 the teeth of the pallet-wheel against it when the motor is not held, as will be hereinafter described. The gong b^{10} is screwed upon the hub a^4 .

B represents a push-button shell, preferably of metal, it having a hollow or open concavity, as shown at the right in Fig. 1. This concavity is partially filled from the inner side of the shell with a push-button c , having a shoulder 2 , the said push-button having 85 the appearance in the surrounding shell of an ordinary push-button of an electric bell, the said button being screwed upon the threaded end of the push-rod c^2 . The push-rod c^2 is extended through a hole c^3 in a door, 90 or it may be in frame-work of the building and through the base a , and it is thereafter, as herein shown, screwed into a spindle c^4 , a part of which is reduced, as shown in Fig. 1, and threaded preferably, as at 3. 95

The part of the push-rod which is threaded, as described, is extended through an arm d , having preferably a long hub d^x , and beyond the end of the arm the portion 3, forming part of the push-rod, is reduced, as at 4, 100 to take bearing in the pillar-plate, a shoulder on the part 3 being acted upon by a forked

spring d' , attached by a suitable screw, as 10, to the pillar-plate, the said spring normally acting to keep the arm d pressed against the side of the pallet-wheel b^6 and the shoulder 2 5 of the push-button against the shell B.

I have herein shown the push-rod and spindle of two pieces, but it might be made in one.

When the gong is put together in its manufacture, the spindle or part c^4 of the push-rod will be turned to lengthen or shorten the 10 effective length of the push-rod, so that the arm d will come firmly against one side of the pallet-wheel, and thereafter when the push-button is pushed in the push-rod in its movement 15 longitudinally will remove the arm d from contact with the pallet-wheel and will permit the same to be rotated by the stress of the spring and gear.

Should the spring d' become weak in use, or 20 should it wear where it comes in contact with the spindle, the push-button may be turned on the outer threaded end of the push-rod with the shoulder 2 in contact with the shell B, thus moving the push-rod and spindle to 25 the right to compensate for loss in strength of the spring or wear between it and the spindle; or, if desired, the apparatus may be dismembered and the spindle turned, but rotation of the push-button is preferred at such 30 time.

I do not desire to limit my invention to the exact shape shown for the push-rod, or of the hammer-carrying arm, or of the spring d' , as I am not aware prior to my invention that a 35 bell has ever had its pallet-wheel held frictionally by or through an arm or projection on a push-shaft.

By the term "gong" I mean any usual sonorous body like a gong or bell.

40 I claim—

1. The gong, a rock-shaft, a hammer and a pallet attached to the rock-shaft, and a pallet-

wheel and means to rotate it, combined with a push-rod, an arm arranged upon the push-rod to come into contact with the face of the 45 pallet-wheel to arrest its rotation, and a spring to force said push-rod and its arm into such contact, substantially as described.

2. The gong, a rock-shaft, a hammer and a pallet attached to said shaft, a pallet-wheel 50 and means to rotate it, combined with a push-rod adjustable as to length and having an arm in frictional engagement with the pallet-wheel to restrain the rotation of the pallet-wheel, and a spring acting upon the push-rod 55 with a tension variable by adjustment of the push-rod, substantially as described.

3. The gong, a rock-shaft, a hammer and a pallet thereon, and a rotary pallet-wheel, combined with a spring-actuated two-part adjustable push-rod and means to prevent the rotation of the pallet-wheel, substantially as 60 described.

4. The push-rod of a gong-bell, composed of a rod c^2 and a spindle c^4 , made adjustable one 65 on the other, combined with a spring normally to move the push-rod in the direction of its length, as and for the purposes described.

5. The gong, a rock-shaft, a hammer and a pallet attached to said shaft, a pallet-wheel, 70 and means to rotate it, combined with a push-rod having an arm, and a spring acting upon 75 said rod to throw the arm against the face of the pallet-wheel and restrain its rotation by frictional contact therewith, substantially as described.

In testimony whereof I have signed my name to this specification in the presence of two subscribing witnesses.

NAHUM JUDSON BUSBY.
